(57) **CLAIM**

We claim the ornamental design for the door for refrigerator, as shown and described.

DESCRIPTION

FIG. 1 is the front perspective view of the door for refrigerator showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof; and,

FIG. 8 is a rear perspective view of the door for refrigerator shown in an example environment.

The broken lines in the drawing show unclaimed environment only and form no part of the claimed design.
